United States Patent Office

Des. 231,145
Patented Apr. 2, 1974

231,145

HAIR CURLER

Ann Di Gaetano, Antonina Di Gaetano, and Giuseppina Di Gaetano, all of 390 Newport, Detroit, Mich. 48215
Continuation-in-part of design application Ser. No. 104,546, Jan. 6, 1971, now Patent No. 226,046, dated Jan. 16, 1973. This application July 13, 1972, Ser. No. 271,366

Term of patent 14 years

The portion of the term of the patent subsequent to Jan. 16, 1987, has been disclaimed

Int. Cl. D28—03
U.S. Cl. D86—10 E

FIG. 1

FIG. 1 is a front perspective view of a hair curler showing our new design;

FIG. 2 is a front elevational view thereof; and

FIG. 3 is a front perspective view of a hair curler showing a modified form of our new design.

The sides not shown in FIGS. 1 and 3 are the same as the sides shown.

This application is a continuation in part of our co-pending design application, Ser. No. 104,546 filed Jan. 6, 1971 now U. S. Design Pat. 226,046 dated Jan. 16, 1973.

We claim:

The ornamental design for a hair curler, substantially as shown and described.
